United States Patent Office.

CHARLES A. PARET, OF NASHVILLE, TENNESSEE.

Letters Patent No. 70,889, dated November 12, 1867.

IMPROVED BLACKING-BRUSH.

The Schedule referred to in these Letters Patent and making part of the same.

TO ALL WHOM IT MAY CONCERN:

Be it known that I, CHARLES A. PARET, of Nashville, in the county of Davidson, and State of Tennessee, have invented a new and improved Blacking-Brush; and I do hereby declare that the following is a full, clear, and exact description thereof, which will enable those skilled in the art to make and use the same, reference being had to the accompanying drawing, forming part of this specification.

This invention relates to an improved blacking-brush, and consists in passing an endless elastic band crosswise through four staples upon the back of the brush-stock, to hold the box of blacking, and in a groove along the side of the stock to receive a scraper.

The accompanying drawing is a perspective view of my improved blacking-brush.

A is the brush-stock, in the side whereof is a groove, in which slides the metal scraper B, held in place by the spring C. D D are four staples or hooks, through which, after passing through the loop F, the endless elastic band E is passed crosswise. The hooks or staples D are constructed so as to leave a small space between the hook and the shank through which the elastic band is slipped, which, when broken, can be easily replaced by another band in the same manner. The band being raised by the loop F, the blacking-box is placed beneath it, and held by it in the position shown in the drawing.

I claim as new, and desire to secure by Letters Patent—

The arrangement of the staples D D, loop F, elastic band E, scraper B, spring C, and grooved brush-stock A, as herein described, for the purpose specified.

CHAS. A. PARET.
